Primary Examiner — Manpreet Matharu*Assistant Examiner* — Aula Soroush*(74) Attorney, Agent, or Firm* — Robert N. Lipszik(57) **CLAIM**

The ornamental design for a tire for automobile, as shown and described.

DESCRIPTION

FIG. 1 is a perspective view of a tire for automobile showing my new design, it being understood that the pattern repeats uniformly throughout the circumference of the tread;
 FIG. 2 is a front elevational view thereof;
 FIG. 3 is a right side elevational view thereof; the left side being a mirror image thereof; and,
 FIG. 4 is an enlarged fragmentary front elevational view taken from 4-4 of FIG. 2.

1 Claim, 4 Drawing Sheets---
